UNITED STATES PATENT OFFICE.

JAMES A. CAMERON, OF NEW YORK, N. Y.

LIGHT-SHIELD FOR MOVING-PICTURE MACHINES.

1,005,935.

Specification of Letters Patent. Patented Oct. 17, 1911.

Application filed November 21, 1910. Serial No. 593,334.

To all whom it may concern:

Be it known that I, JAMES A. CAMERON, a citizen of the United States, and a resident of the borough of Brooklyn, in the county of 5 Kings, city and State of New York, have invented certain new and useful Improvements in Light-Shields for Moving-Picture Machines, of which the following is a specification.

10 The principal object of my invention is to protect the film from the heat of the lantern or source of light.

As well known in the moving picture art, a very strong light has to be used for projecting the pictures, and the heat generated by this intense light is considerable. Unless the film is properly protected from the heat, it is liable to become ignited or otherwise injured. This liability of fire has always 20 been a constant source of danger in moving picture machines, and although fire shields have been proposed heretofore, they have all been more or less inefficient and have only partially protected the film.

25 According to my present invention, the film is effectually protected from the heat of the light source by interposing a shield between the projector or moving picture machine and the source of light, and by 30 providing a free air space between the fire shield and the machine itself. In its preferred form the fire shield consists simply of a substantially flat plate of metal or other non-inflammable material, which is supported in front of the projector and is provided with an opening in line with the exposure opening of the machine. By reason 35 of this arrangement all superfluous light rays are intercepted before they reach the

40 machine, and the beam of light which passes through the opening in the shield may be made to correspond in size to the exposure opening of the machine. The beam of light may thus be reduced to the proper size in 45 advance of the exposure opening, and by so being of just the proper size to pass through the exposure opening, it will impart practically none of its heat to the mem-

ber in which the exposure opening is formed. And furthermore, any heat that may be 50 absorbed by the fire shield is prevented from being communicated to the machine and thus to the film, by the existence of the free air space between the shield and the machine.

Another great object of my invention is 55 to interconnect the fire shield with the moving picture machine or with the lantern so that the machine cannot be operated without the fire shield being first in operative position. This result may be accomplished 60 in various ways. For instance, the fire shield may be operatively connected with a movable part of the moving picture machine, such as a gate for holding the film in proper 65 relation to the exposure opening, in such a way that the shield will be moved to its operative position when the gate or other part is moved to the proper position for operation of the machine.

Various other objects and features of the 70 invention will appear as the specification proceeds.

In the accompanying drawings I have illustrated a preferred embodiment of my invention but I would have it understood that 75 various modifications and changes may be made therein without departing from the spirit and scope of the invention.

In the drawings Figure 1 is a view partly in section and partly in side elevation of a 80 moving picture machine, showing an embodiment of my invention applied thereto. Fig. 2 is a front elevation of the invention taken at right angles to Fig. 1.

Like reference characters denote corresponding parts throughout the several views.

The invention in its simplest form consists preferably of a plate 1 of suitable material, such as sheet steel, which is interposed 90 between the lantern or source of light 2 (shown diagrammatically in Fig. 1) and the projector or moving picture machine 3. The moving picture machine is provided with the customary exposure opening 4 through 95 which the beam of light passes on its way to

the screen. This exposure opening may be formed in a film support 5 over which the film passes, and for the purpose of holding the film in its proper relation to the exposure opening, the machine may be provided with a holding device of some sort such as the gate 6. This gate is of course provided with an opening 7 in line with the exposure opening of the machine. To permit of the film being threaded through the machine, this gate or holding member is preferably capable of a movement toward and away from the film support and for this reason the gate may be mounted to swing on a pivot 8. A latch 9 may be utilized for normally holding the gate in clamping relation with respect to the film. The film, as is well known, is given an intermittent advancing movement through the machine, suitable means being employed for imparting this advancing movement to the film. Inasmuch as the means for intermittently advancing the film forms no part of the present invention, such means has not been illustrated. At the time of imparting the intermittent advancing movement to the film, it is highly desirable that the tension of the holding member or gate upon the film be temporarily released. For this reason some means are usually provided for intermittently releasing the pressure of the gate or holding member. These means may consist of a cam 10 engaging a roll 11 on the lever 12 which carries the latch 9. A spring 13 normally holds the gate closed under proper tension and the cam 10 just described acts to intermittently release the pressure of the gate on the film. This intermittent clamping device, as just described, forms no part of the present invention and has only been brought in to better bring out the relation of the fire shield to the moving picture machine.

The fire shield may be supported in front of the exposure opening of the machine in any suitable way. Preferably, however, it is supported by the machine itself so as to in fact form a portion of the moving picture machine. In order that the fire shield will not interfere with the action of the gate when the same is opened, to permit threading of the film through the machine, the shield is preferably pivotally supported at a point near the upper end of the machine. And the shield may in fact be engaged on the same pivot 8 upon which the gate is swung. By an arrangement such as this the fire shield will be swung open by the movement of opening the gate and without in any way interfering with the action of the said gate (see dotted lines in Fig. 1). The arrangement just described also provides for the free air space 14 between the fire shield and the film support or other member which carries the exposure opening.

As a device to prevent the machine from being operated before the fire shield is in proper position, the fire shield is preferably interconnected with one of the parts of either the moving picture machine or the lantern, so that the fire shield must be moved to operative position before the machine is capable of being operated. This may be provided for in a very simple way by the use of an abutment carried by the gate and adapted for engagement with the fire shield to position the same when the gate is closed. This abutment may simply be in the form of a screw 15 carried by the gate, the stem of the screw passing through an opening 16 in the shield, and the head of the screw engaging with the face of the shield when the gate is closed. The shield is thus supported in front of the exposure opening in such a way as not to interfere with the intermittent clamping action of the gate or holding member, and at the same time the parts are so interlocked that the gate cannot be closed without positioning the fire shield. It is usually desirable in threading the film through the machine to hold the gate open during the threading process. As a convenient means for thus holding the gate open, the fire shield may be provided with a pivoted lever 17 which, when the parts are thrown open, as in the dotted lines in Fig. 1, will fall down, and engaging with the table or other support, hold the gate and fire shield in open position.

The fire shield may be made in any desired shape, but in any event it preferably has the central portion thereof enlarged so as to intercept all the superfluous light rays issuing from the light source (see Fig. 2). An opening 18 is provided in the shield in alignment with the exposure opening of the machine for the passage of the beam of light to the machine. This opening is preferably made of the proper size to reduce the beam of light to just the right proportions to pass through the exposure opening of the machine. In this way all superfluous light rays are intercepted and since the beam of light, when it reaches the exposure opening, is either exactly or approximately the size of such exposure opening, it will impart practically none of its heat to the member in which the exposure opening is formed.

In connection with my invention I prefer to employ a fire shutter 19 for intercepting the beam of light when the machine is at rest. This fire shutter is preferably located in front of the opening in the fire shield, and the shutter itself may be conveniently supported by the gate, as indicated at 20 in Fig. 1. This shutter may be of what is known as the centrifugal type, in which a centrifugal governor 21, carried in the balance wheel 22 of the machine (see Fig. 2)

acts upon a lever 23 to open or close the fire shutter, according as to whether the machine is running or at rest. This fire shutter is not of my own invention and I only claim it in its connection with the fire shield.

5. What is claimed is:

1. In combination with a moving picture machine having a member provided with an exposure opening therein, a gate arranged to coöperate with the said member, a pivotal support for said gate, and a fire shield engaged on the said pivotal support so as to have a movement corresponding to the swinging movement of the gate.

10. 2. In combination with a film support, a swinging gate arranged in clamping relation thereto, means for actuating said gate to intermittently clamp and release the film passing between the gate and film support, a fire shield disposed in spaced relation to the gate, having a swinging movement corresponding to the opening and closing movement of the gate, and means for supporting said fire shield whereby it will be unaffected by the clamping action of the gate.

15. 3. In combination, a moving picture machine having a movable part which must occupy a certain position when the machine is to be operated, and a fire shield supported independent of the movable part and operatively connected with said movable part, whereby said fire shield will be moved to operative position when the movable part is moved into position for the operation of the

20. 35. machine. 4. In combination, a moving picture machine having a film holding member movable into and out of holding engagement with the film, and a fire shield supported independent of the film holding member and operatively connected with the film holding member whereby the film holding member when moved into operative engagement with the film will move the fire shield into its operative position.

40. 45. 5. In combination, a moving picture machine provided with a film holding gate movable into and out of holding engagement with the film, a fire shield supported independent of and in front of the gate and movable to permit the gate being swung open when the film is to be inserted in the machine, and means connecting the fire shield with the gate whereby the fire shield will be moved to operative position when the gate is closed.

50. 6. The combination with a moving picture machine provided with a film support and a swinging gate adapted to hold the film against the film support, of a fire shield arranged in front of the gate and adapted to be moved by the opening and closing of the gate with respect to the film support.

60. 65. 7. In combination, a moving picture machine having a member provided with an

exposure opening therein, a gate for holding the film in operative relation to the exposure opening movable toward and away from the member aforesaid, a fire shield located in front of the gate, and a means of connection 70 between the gate and shield whereby when the gate is closed in operative position the shield will be likewise moved to operative position.

8. In combination with a moving picture 75 machine, a fire shield pivoted horizontally on the upper portion of said machine and adapted to swing open with respect to the machine, and means for holding the said shield in its open position.

9. In combination with a moving picture machine, a fire shield suspended from a horizontal pivot mounted at the upper end of the machine whereby the lower end of the shield may be swung open with respect to the machine, and a pivoted lever carried by the shield adapted to fall down as the shield is opened to support the shield in such open position.

10. In a moving picture machine, a film 90 support provided with an exposure opening therein, a gate pivoted at its upper end on a horizontal pivot so as to be capable of swinging toward and away from the film support, and a fire shield located in front of the 95 gate and also suspended from a horizontal pivot so as to be capable of a swinging movement in unison with the swinging movement of the gate.

11. In a moving picture machine, a film 100 support provided with an exposure opening therein, a gate pivoted at its upper end on a horizontal pivot so as to be capable of swinging toward and away from the film support, means for actuating said gate to intermittently clamp and release the film passing between the gate and film support, and a fire shield located in front of the gate and also suspended from a horizontal pivot so as to be capable of a swinging movement in 110 unison with the swinging movement of the gate.

12. In combination with a film support, a gate arranged in clamping relation thereto, means for actuating said gate to intermittently clamp and release the film passing between the gate and film support, a fire shield disposed in spaced relation in front of the gate, and means for supporting said fire shield independent of the gate whereby 115 it will be unaffected by the clamping action of the gate.

13. In combination with a film support, a swinging gate arranged in clamping relation thereto, means for actuating said gate 125 to intermittently clamp and release the film passing between the gate and film support, a fire shield disposed in spaced relation to the gate capable of a swinging movement in 130 unison with the opening and closing move-

ment of the gate, and means for supporting said fire shield whereby it will be unaffected by the clamping action of the gate.

14. In combination with a film support, a gate arranged in clamping relation thereto and supported on a horizontal pivot so as to be capable of a swinging movement toward and away from the film support, means for actuating the gate to intermittently clamp and release the film passing between the gate and film support, and a fire shield located

in front of the gate and suspended from a horizontal pivot so as to be capable of a swinging movement in unison with the opening and closing movement of the gate. 15

Signed at New York in the county of New York and State of New York this 4th day of Nov. A. D. 1910.
